United States Patent

Des. 239,566
Patented Apr. 13, 1976

239,566

NONWOVEN FABRIC OR SIMILAR ARTICLE

Clifford M. Vogt, Neenah, Wis., assignor to Kimberly-Clark Corporation, Neenah, Wis.

Filed Oct. 29, 1974, Ser. No. 518,710

Term of patent 14 years

Int. Cl. D5—06

U.S. Cl. D59—2 R

FIG. 1

FIG. 2

FIG. 1 is a plan view of a nonwoven fabric showing my new design; and

FIG. 2 is an enlarged fragmentary view thereof.

I claim:

The ornamental design for a nonwoven fabric or similar article, as shown.
